(57) **CLAIM**

The ornamental design for a bench cushion, as shown and described.

DESCRIPTION

FIG. 1 is a front view of the bench cushion;

FIG. 2 is a rear view thereof;

FIG. 3 is a top view thereof;

FIG. 4 is a bottom view thereof;

FIG. 5 is a left side view thereof;

FIG. 6 is a right side view thereof;

FIG. 7 is a perspective view thereof;

FIG. 8 is another perspective thereof;

FIG. 9 is an enlarged view of portion 9 shown in FIG. 8;

FIG. 10 is an enlarged view of portion 10 shown in FIG. 2;

FIG. 11 is an enlarged view of portion 11 shown in FIG. 3; and,

FIG. 12 is an enlarged view of portion 12 shown in FIG. 7.

The dash-dot lines in FIGS. 2, 3, 7, 8, 9, 10, 11, and 12 illustrate the boundaries of the enlarged view indicators and form no part of the claimed design.
